UNITED STATES PATENT OFFICE.

DAVID FEIGLY, OF MEDWAY, OHIO.

DESIGN FOR SHOVEL FOR POTATO-DIGGERS.

SPECIFICATION forming part of Design No. 16,464, dated January 12, 1886.

Application filed November 9, 1885. Serial No. 182,313. Term of patent 14 years.

To all whom it may concern:

Be it known that I, DAVID FEIGLY, a citizen of the United States, residing at Medway, in the county of Clark and State of Ohio, have invented a certain new and useful Design for Shovels for Digging Potatoes, &c.; and I do declare the following to be a full, clear, and exact description of the invention, such as will enable others skilled in the art to 10 which it appertains to make and use the same, reference being had to the accompanying drawings, and to letters or figures of reference marked thereon, which form a part of this specification.

15 Figure 1 of the drawings is a representation of this invention, and is a perspective view. Fig. 2 is a vertical section. Fig. 3 is a view of the under side.

This design has relation to shovels for digging potatoes; and it consists of the fluke-form angular blade having convex converging front edges and concave rear edges bounding its wings and its points, which is bent at a lower angle than the plane of said wings, and the 20 parallel upwardly convex fingers extending rearwardly from the rear edge of the blade, all as will be hereinafter more fully set forth and claimed.

In the accompanying drawings, the letter A 25 designates the blade of the shovel, which is fluke form and isometrical. Its angular point *a* is a little greater than a right angle, and is bounded by curved convex edges *b*, which are beveled on the under side. These curved

convex edges *b* extend outward and rearward 35 to the ends of the wings *c*, which taper, and are bounded in rear by the convex edges *d*, which extend to near the middle of the back blade, where the fastening lug *e* is formed, projecting upward and rearward from the plane 40 of the wings, which is at a higher angle than the plane of the point *a*, the latter being bent to a lower angle, as indicated.

K K are parallel fingers, which extend rearward and upward from the rear of the fluke-form blade, said fingers being round in cross-section and concavo-convex longitudinally. The ends of these fingers are nearly in the same transverse line and plane, as shown in the drawings.

Having described this invention, what I claim, and desire to secure by Letters Patent, is—

The design for a potato-digger shovel, consisting of the fluke-form angular blade having 55 convex converging front edges and concave rear edges bounding its wings and its points, which is bent at a lower angle than the plane of said wings, and the parallel upwardly-convex fingers extending rearward from the rear edge of the blade, as shown and described.

In testimony whereof I affix my signature in presence of two witnesses.

DAVID FEIGLY.
